UNITED STATES PATENT OFFICE

RALPH P. DOUGHERTY, OF PORTLAND, OREGON

DESIGN FOR A SOUSAPHONE

Application filed February 27, 1932. Serial No. 43,018. Term of patent 14 years.

To all whom it may concern:

Be it known that I, RALPH P. DOUGHERTY, a citizen of the United States, residing at Portland, in the county of Multnomah and State of Oregon, have invented a new, original, and ornamental Design for Sousaphone, of which the following is a specification, reference being had to the accompanying drawings, forming part thereof.

Fig. 1 is a side view of the article, showing my new design.

Fig. 2 is a rear view.

Fig. 3 is a front view.

I claim:

The ornamental design for a sousaphone, as shown.

RALPH P. DOUGHERTY
